(57) **CLAIM**

I claim the ornamental design for an invertible plush toy, as shown and described.

DESCRIPTION

FIG. 1 is an upper right front perspective view of the invertible plush toy comprising the present invention;

FIG. 2 is an upper left rear perspective view thereof;

FIG. 3 is a right side view thereof;

FIG. 4 is a front view thereof;

FIG. 5 is a rear view thereof; and,

FIG. 6 is a top view thereof.

The broken line showing of the zipper is for illustrative purposes only, and forms no part of the claimed design.
